UNITED STATES PATENT OFFICE.

FRANK A. WEBB, OF PROTECTION, KANSAS.

CARBID CONTROLLING AND DUMPING VALVE FOR ACETYLENE-GAS GENERATORS.

1,337,805.

Specification of Letters Patent. Patented Apr. 20, 1920.

Application filed December 22, 1916. Serial No. 138,434.

To all whom it may concern:

Be it known that I, FRANK A. WEBB, a citizen of the United States, residing at Protection, in the county of Comanche and

5 State of Kansas, have invented certain new and useful Improvements in Carbid Controlling and Dumping Valves for Acetylene-Gas Generators; and I do hereby declare the following to be a full, clear, and
10 exact description of the invention, such as will enable others skilled in the art to which it appertains to make and use the same.

The invention relates to improvements in carbid controlling and dumping valves for
15 acetylene gas generators.

The object of the present invention is to improve the construction of acetylene gas generators and more especially the construction of the carbid holder and the carbid controlling and dumping valve and to provide a simple, practical and efficient valve of this character capable of discharging a charge of carbid of the same size at each operation and equipped with means for
20 cutting off the supply of carbid to the valve when the valve is inclined upwardly at any angle to the horizontal whereby the loss of carbid is prevented in case the valve should stick in any position from a horizontal to a
25 full dumping position.

Another object of the invention is to provide a carbid controlling and dumping valve of this character which will not discharge when in a horizontal position or any
30 position between a horizontal and its full closed position.

With these and other objects in view, the invention consists in the construction and novel combination of parts hereinafter fully
40 described, illustrated in the accompanying drawing, and pointed out in the claims hereto appended; it being understood that various changes in the form, proportion, size and minor details of construction, within
45 the scope of the claims, may be resorted to without departing from the spirit or sacrificing any of the advantages of the invention.

In the drawing—

50 Figure 1 is a vertical sectional view of a portion of a carbid holder and a carbid controlling and dumping valve constructed in accordance with this invention,

Fig. 2 is an elevation of the same, in the
55 position shown in dotted lines in Fig. 1,

Fig. 3 is a detail perspective view of the carbid controlling and dumping valve,

Fig. 4 is a detail sectional view illustrating the arrangement of the combined stop and reinforcing plate.

60

Fig. 5 is a vertical sectional view illustrating another arrangement of the plate or partition.

Like numerals of reference designate corresponding parts in the several figures of 65 the drawing.

In the accompanying drawing in which is illustrated the preferred embodiment of the invention, 1 designates an automatically operated carbid controlling and dumping 70 valve composed of spaced side walls, a connecting bottom 2, and a curved rear end wall 3. The valve 1 is connected by a transverse pintle 4 to the lower tapered portion 5 of a carbid holder of an acetylene gas 75 generator. The tapered portion 5 is flattened at two of its side walls and it is provided at one of its walls with an outlet 6 and the opposite wall 7 has an inclined portion 8 extending downwardly from the bottom of the outlet and having a transversely disposed eye 9 for the reception of the pintle or pivot 4. The pintle or pivot 4 extends through the side walls of the carbid 80 dumping and controlling valve which extends in advance and in rear of the pintle or pivot and the forwardly extending portion is cut away at the side walls at 10 to form a discharge mouth or spout. The valve 1 extends downwardly and rearwardly at an inclination as illustrated in 85 full lines in Fig. 1 of the drawing when in a non-feeding or carbid receiving position

and it assumes an oppositely inclined position as illustrated in dotted lines in Fig. 1 of 90 the drawings when in a feeding or carbid discharging position. The valve has a receiving end and a discharging end. When the valve is in carbid receiving position its receiving end is lowermost, and when the 95 valve is in carbid discharging position its discharging end is lowermost. In order to enable the valve to deliver or discharge a charge of carbid of the same size at each operation, and prevent any leakage of the 100 carbid from the carbid holder to the valve should the valve for any reason stick in its feeding operation, the valve is provided with a plate or partition 11 extending across the said valve midway between the upper 105 and lower edges of the side walls and fixed to the same and arranged in parallelism with the bottom wall or portion of the valve. The plate or partition 11 is mounted

eccentrically with relation to the transverse pin or pintle with its inner edge arranged contiguous to the transverse eye of the pivot or hinge joint and in the pivotal movement 5 of the valve the plate or partition travels in an arc around the pivotal pintle and is adapted to cut off the supply of carbid to the valve when the plate or partition and the rear portion of the valve is inclined up- 10 wardly at any angle to the horizontal.

When the valve is inclined in the opposite direction the bottom wall or portion 2 will prevent any feeding of the carbid to the acetylene gas generator. By this construction 15 the feed of carbid to the machine is positively controlled and leakage of the carbid and gas is prevented.

The plate or partition 11 is preferably of an area substantially equal to the area of 20 the outlet 6 of the carbid holder and the transverse pin or pintle is arranged in the vertical plane of the lower edge of the wall 12 at top of the outlet 6. Also the pivot or pintle is arranged midway between the 25 upper and lower edges of the side walls of the valve and the curved rear wall is arranged on an arc of a circle having its center at the outer or rear edge of the plate or partition and the said curved arcuate rear wall is preferably approximately 25 degrees 30 less than a semi-circle but the proportions of the parts may be varied as will be readily understood. When the valve is in its non-feeding position as illustrated in full lines 35 in Fig. 1 of the drawing, the carbid from the carbid holder will flow into the valve until the latter receives a full charge and when the valve is operated to dump the charge, the plate or partition will move upwardly as the mouth or discharge end of 40 the valve moves downwardly and the supply or feed of the carbid will be cut off to the valve while the valve is in its feeding position. The spout or front end of the 45 valve is connected by a transverse pintle 13 with the lower end of an operating rod 14 designed to be connected with the bell not shown or other operating member of the acetylene gas generator and when the rod 50 moves downwardly with respect to the valve, the latter will be opened or moved to its seating position and when the operating rod is raised the valve will be carried to its non-feeding position. The inclined bottom 55 portion 8 of the wall 7 at the outlet of the carbid holder is equipped at its lower outer face with a combined reinforcing and stop plate 15 suitably secured to the inclined portion 8 and having the side edges 16 bent 60 at right angles to form projecting flanges which are arranged in the path of and adapted to be engaged by the pivot 13 of the operating rod 14. The valve is equipped at its rear end with a weight 17 which 65 is adapted to positively return the valve

to its non-feeding position after a charge has been dumped.

In Fig. 5 is illustrated another form of the invention in which the plate or partition 11^a is arranged at an angle to the bottom of the pivoted valve. The plate or partition extends downwardly and rearwardly from the transverse pivot or pintle of the valve when the bottom of the latter is in a horizontal position and it has been found 75 that the plate or partition may be arranged at such an inclination variable from five to fifteen degrees more or less.

What is claimed is:—

1. In combination, a carbid holder having a discharge opening, a downwardly inclined extension carried by said carbid holder and disposed below said discharge opening, a valve having a receiving and a discharge end and horizontally pivoted intermediate its ends to said extension, said valve being adapted to be moved into an inclined carbid receiving position with its receiving end lowermost and into a reversely inclined carbid discharging position with 90 its discharging end lowermost, a weight normally holding the valve in carbid receiving position, a cutoff plate carried by said valve and having one of its longitudinal edges contacting with the lower edge of 95 said extension, said cutoff plate being in the plane of said extension when the valve is in carbid receiving position and at an angle to said extension when the valve is in carbid discharging position, a rod extending transversely of and carried by the valve and adapted to engage the under side of said extension to limit the movement of the valve under the influence of said weight, and an operating rod connected to said rod. 100

2. In combination, a carbid holder having a discharge opening, a downwardly inclined extension carried by said carbid holder and disposed below said discharge opening, a valve horizontally pivoted intermediate its ends to said extension and having a carbid receiving end and a carbid discharge end, a cutoff plate carried by said valve and having one of its longitudinal edges contacting with the lower edge of said 115 extension, and means adapted to move the valve into carbid receiving position and into carbid discharging position, said cutoff plate being located in the plane of said extension when the valve is in carbid receiving position and at an angle to and extending above said extension when the valve is in carbid discharging position. 120

In testimony whereof I affix my signature in presence of two witnesses.
